UNITED STATES PATENT OFFICE.

FRED E. GROSVOLD, OF EAU CLAIRE, WISCONSIN.

COAL-CHUTE.

1,312,498.

Specification of Letters Patent.

Patented Aug. 5, 1919.

Application filed June 20, 1918. Serial No. 240,960.

To all whom it may concern:

Be it known that I, FRED E. GROSVOLD, a citizen of the United States, and a resident of Eau Claire, in the county of Eau Claire and State of Wisconsin, have invented a new and Improved Coal-Chute, of which the following is a full, clear, and exact description.

My invention relates to chutes for coal and has reference more particularly to means for automatically locking the chute in closed position.

The object of the invention is to provide a simple and inexpensive coal chute which is provided with a suitable latch mechanism which can be placed into inoperative position to allow the chute to be raised, and which chute has means for operating the latch as the chute is raised to place said latch in position to automatically lock the chute when the same is closed.

With the above and other objects in view, the nature of which will more fully appear as the description proceeds, the invention 25 consists in the novel construction, combination and arrangement of parts as herein-after fully described, illustrated and claimed.

In the accompanying drawings forming 30 part of the application similar characters of reference indicate corresponding parts in all the views.

Figure 1 is a face elevation of the chute;

Fig. 2 is a vertical section on the line 2—2,

35 Fig. 1;

Fig. 3 is a section on the line 3—3, Fig. 2;

Fig. 4 is a section similar to that of Fig. 2, showing the chute door partially raised, the latch being in position to automatically lock 40 the chute when the door is closed;

Fig. 5 is an enlarged sectional view through the chute with the door closed when the latch is placed into the inoperative position; and

45 Fig. 6 is a cross section on the line 6—6, Fig. 5.

Referring to the drawings, 7 is a tubular housing, the ends of which are cut obliquely to the walls of the housing so that the same 50 is placed into an inclined or oblique position relative to the wall 8 to present the ends of the housing in a substantially vertical position, the outer end of the housing being positioned above the inner end, the outer end extending forward of the wall 8 so that no obstruction interferes with the movements

of the cover 9 which is mounted to slide in grooves 10 provided in the sides of the tubular housing 7. The upper end of the door 9 is bent to form a flange 11 so that it 60 will make a stop for the door. The door has also a raised portion 12 forming a grip for the hand to manipulate the door.

The housing 7 is preferably of angular cross section. In one of the upper corners a 65 rod 13 is mounted to slide. Upon the rod 13 two spaced collars 14^a and 14^b are secured and upon the rod between the said collars, a collar 14 provided with a hook-shaped finger 15, is loosely mounted. The finger 15 70 extends through a slot 16 in a casing 17 which is secured to the housing 7. The slot 16 has an inclined slot portion 18 which serves as a cam surface for the finger 15 and causes the rod 13 to slide, when the finger 75 is aligned with the inclined slot portion 18, under the influence of a spring 19 which is mounted on the rod 13 and one end of which abuts against the casing 17 and the other end against the collar 14^b.

When the finger 15 is in the straight position of the slot 16 the rod is held retracted to permit the door to be raised. To bring the finger 15 within the straight portion of the slot 16, the rod 13 must be drawn against 85 the resistance of the spring 19, when the finger 15 will by gravity enter the straight portion of the slot 16 thereby clearing the projection 20 on the door 9, consequently the door 9 can be raised when the latch mechanism is in that position.

The door 9 carries also an inwardly directed extension 21 which lies in vertical alignment with the finger 15 when the same is in the straight portion of the slot 16 (see 95 Fig. 6) thereof. As this extension comes in contact with the finger 15 it moves the finger into alignment with the inclined portion 18 of the slot thereby allowing the spring 19 to move the rod 13 forwardly or into operative position (see Fig. 4). As the door descends, the extension 21 will not be in a vertical plane with the finger 15 which is in the operative position (see Fig. 6, dotted position of the finger) but the rod 13 will be in 100 the path of the projection 20 and the same will be pushed back until the projection 20 passes, when the rod snaps back under the action of the spring 19 and locks the door 9 in the closed position (see Fig. 2). 110 It is evident that the projection 20 is not sufficiently long to bring the finger 15 into

engagement with the straight portion of the slot 16 so as to place said latch mechanism into inoperative position.

Having thus described my invention, I claim as new and desire to secure by Letters Patent:—

1. In a coal chute, a slidably mounted door, a spring-actuated latch locking the door in a closed position, means for maintaining the latch in inoperative position whereby the door may be raised, and means carried by the door adapted to place the latch into operative position after the door has been partly raised whereby when the door is closed said latch will automatically lock the door in the closed position.

2. In a coal chute, a slidably mounted door, a spring actuated latch for locking the door in closed position, means for retaining the latch in inoperative position, and means carried by the door for placing the latch into operative position when the door is moved to the open position so that when the door is closed the latch will automatically lock the door in closed position.

3. In a coal chute, a slidably mounted door, a spring actuated latch for locking the

door in a closed position, a finger constrained to move with the latch, a casing for said latch having a cam groove engaged by 30 the finger, and an extension from the door for operating the finger while the door is raised to place the latch into operative position.

4. In a coal chute, a slidably mounted 35 door, a rod mounted to slide to and from the door, a casing, a spring in said casing engaging the rod for moving the rod to the door, a collar on said rod, a finger on said collar, a cam-shaped groove in said casing 40 engaged by the finger, said groove having a straight portion adapted to be engaged by the finger whereby the spring is rendered inoperative and whereby the rod is maintained away from the door, and an extension 45 on said door adapted to be in the way of the finger when the same engages the straight portion of the groove and whereby said finger is operated and the spring rendered operative to move the rod toward the door 50 whereby when the door is closed said rod automatically locks said door.

F. E. GROSVOLD.

Copies of this patent may be obtained for five cents each, by addressing the "Commissioner of Patents, Washington, D. C."
